(57) **CLAIM**

I claim the ornamental design for a bobber shaped urn, substantially as shown and described.

DESCRIPTION

FIG. 1 is a front elevation view of the bobber shaped urn. FIG. 2 is a top elevation view of the bobber shaped urn. FIG. 3 is a front exploded view of the bobber shaped urn; and, FIG. 4 is a bottom elevation view of the bobber shaped urn. The broken line portions of the drawings are for illustrative purposes only and form no part of the claimed design.
